UNITED STATES PATENT OFFICE.

CHIEO A. LARUE, OF WISCONSIN RAPIDS, WISCONSIN, ASSIGNOR TO AMERICAN CAR-
BONIC MACHINERY COMPANY, OF WISCONSIN RAPIDS, WISCONSIN.

REFRIGERATOR.

Application filed October 18, 1922. Serial No. 585,941.

This invention relates to refrigerators, particularly those of the iceless type in which the refrigeration is obtained by circulating a refrigerant through a cooling coil, and has for its object the provision of an attachment for refrigerators useful in apartments and other houses, by means of which water may be frozen into small cubes for use in preparing iced drinks and for other purposes.

The preferred embodiment of my invention provides a simply constructed metallic jacket for enclosing the refrigerating coils which are located adjacent one wall of the refrigerator, said jacket having openings leading to pan-supporting shelves upon which pans of water to be frozen are placed, said shelves being located in the spaces between successive convolutions of the coils and therefore requiring no additional space, the jacket being capable of installation in already existing refrigerators without involving any changes in the construction thereof. This construction provides practical means for concentrating, the cooling effect adjacent the ice pans, so as to cause rapid and economical freezing of the pans, without wasting refrigeration, and without maintaining the temperature in the major portion of the refrigerator below the normal.

To the attainment of the foregoing the invention consists in the construction and arrangement to be hereinafter described and claimed, though it should be distinctly understood that the matter illustrated and described is merely the preferred embodiment of the invention, and the right is reserved to make all such changes as will not vary from the salient features or depart from the spirit of the invention as defined in the appended claims.

In the drawings, forming a part of this specification:—

Fig. 1 is a vertical section through a typical refrigerator looking toward the back wall thereof and showing my attachment in place with a portion thereof broken away.

Fig. 2 is a vertical section at right angles to Fig. 1, showing my device in elevation with parts broken away and in section.

Figs. 3 and 4 are views similar to Figs. 1 and 2, respectively, but showing a modification.

Referring more particularly to the drawings, the letter A designates a conventional

refrigerator which includes an outer wall or casing B, an inner wall or casing C, separated from the outer wall by insulating material D, and lined with metallic or other sheathing or lining material E, and which further includes shelves F for supporting articles to be kept cool. The front of the refrigerator has the usual openings closed by suitable doors G. These elements are of the usual construction and no claim is made thereon.

Refrigerators of the type in which no ice is used are provided with cooling coils through which a refrigerant, such as brine, is passed to and from a mechanical refrigerating plant located at a central station at a more or less distant point. In Figs. 1 and 2, I have shown the cooling coil H as being of a pipe construction arranged in serpentine form, the various coils being arranged one above another near the back wall, and connected with inlet and outlet pipes I and J, respectively, by means of suitable connections K, while in Figs. 3 and 4, I have shown the coil L as of the radiator type, that is, it is formed as a casing having a series of openings L' extending from front to back thereof. This casing is of course connected with inlet and outlet pipes M and N, respectively. The coils shown are known as flat coils, and are approximately one inch or one inch and a quarter in diameter.

The letter O (Figs. 2 and 4) designates a drain which carries off water which condenses upon and drips from the coils, and also serves as a general drain for the refrigerator, the bottom of the refrigerator where the drain is connected being sunken or depressed to form a well.

In carrying out the present invention, I provide a removable jacket 10, which is closed at its front, sides and top and open at its bottom and rear. This jacket is preferably formed from a single piece of sheet metal, such as galvanized iron, or the like, which may be painted, enameled or otherwise treated, to present a pleasing appearance and to add to its durability by providing against corrosion. This jacket fits about and encloses the cooling coils with its lower end resting upon the bottom of the refrigerator directly over the drain O, and with its open back closed by the rear wall of the refrigerator. Various means may be employed for holding this jacket in place,

- though in actual practice, I prefer turn buttons 11, pivoted on the back wall of the refrigerator and engaging over lateral flanges 12 formed on the sides of the jacket. This particular securing means permits ready removal of the jacket, whenever such may be found desirable. To allow for the inlet connection one side of the jacket may be cut away as indicated at 13.
- 10 At various points, the front of the jacket has a series of openings 14 arranged opposite the spaces between the convolutions of the coils II, and normally closed by doors 15, which are here illustrated as being hinged above the openings, but which might be otherwise mounted. Extending rearwardly at the bottom of each opening is a shelf 16, which, in actual practice, is preferably formed by bending rearwardly the metal of the front wall between the cuts defining the openings 14, though I do not wish to be restricted in this matter, as the shelves might be formed as separate pieces and soldered, riveted or otherwise secured to the front wall of the jacket about said openings. These openings and their doors are disposed above the shelves F, and access thereto may be obtained through the usual doors of the refrigerator.
- 20 The numeral 17 designates pans, in which is placed the water to be frozen, and these pans are here illustrated as being provided with various partitions 18, which form relatively small compartments. The pans are necessarily of a size to pass easily through the openings 14, and they are preferably provided with handles 19 which may consist merely of a rolled over edge. These details are stated, but they are not material to this invention.
- 25 In the use of the device, the doors 15 are swung open, and the pans of water placed upon the shelves 16, after which the doors are allowed to return by gravity to their closed position. The cooling action of the refrigerant passing through the coils will, of course, operate to freeze the water in an obvious manner, so that when the pans are removed after the lapse of the required time, they may be inverted to discharge or release the blocks or cubes of ice, and replaced in the refrigerator for further use.
- 30 A feature of my invention resides in a removable jacket forming an enclosure for the refrigerating coils and the ice pans supported in connection therewith, which enclosure forms a place for freezing the water in the ice pans. This jacket or enclosure has no additional insulation, as the usual insulation of the refrigerator answers all the purposes. The jacket extends from the top to the bottom of the cooling coil, enclosing the entire coil, and at the bottom connects with the drain O, which as before stated, serves the purpose of a drain for the refrigerator as well as the drain for the enclosure. The coils employed are of the usual construction, and the invention may be applied to any refrigerator after it is constructed, it being noted in this connection that the front 70 of the jacket constitutes the rear wall of the food compartments of the refrigerator. While I have shown the invention in connection with the rear wall of the refrigerator, and this is the most desirable arrangement, it could be applied to one of the side walls with satisfactory results. The invention does not materially trespass upon the food-receiving compartment of the refrigerator. 75
- 35 By reason of the fact that the cooling coils are enclosed and the refrigeration is confined thereto, the contents of the ice pans may be quickly frozen without lowering the temperature of the refrigerator beyond the usual degree.
- 40 From the foregoing description, and a study of the drawings, it will be apparent that I have thus provided a simple and practical means for producing ice for domestic or other purposes, the jacket operating to concentrate the cooling action of the refrigerant passing through the coil so as to effect the freezing without employing a refrigerant circulating at an excessively low temperature. As the attachment is so simple, its cost will be low while it will efficiently operate to perform the function for which it is intended.
- 45 What is claimed is:—
1. In a refrigerator having a provision chamber, the combination with a vertically extending cooling coil through which is passed a refrigerant, a jacket forming with the refrigerator wall an enclosure for the coil and also forming one of the walls of the provision chamber, said jacket having openings opposite certain spaces between the convolutions of the coil, and supports at the openings extending into the enclosure 100 for supporting water pans. 105
2. In a refrigerator having a provision chamber, the combination with an upright cooling coil through which is passed a refrigerant, a removable metallic jacket forming with the wall of the refrigerator a non-insulating enclosure for the coil and also forming one of the walls of the provision chamber, said jacket provided with openings arranged opposite the spaces between the coil convolutions, and shelves within the enclosure at said openings adapted to support water containing pans so that each of said pans will be substantially surrounded by one convolution of the cooling coil. 110
3. In a refrigerator having a provision chamber, the combination with an upstanding cooling coil for the passage of a refrigerant arranged adjacent one wall of the refrigerator, a jacket extending from the top 115

- to the bottom and forming with one side wall of the refrigerator an enclosure for the coil and also forming one of the walls of the provision chamber, said jacket having 5 openings, supports within the jacket adjacent the openings for supporting pans containing water, and means for detachably securing the jacket against said wall of the refrigerator.
- 10 4. An attachment for ordinary household refrigerators having a vertical refrigerating coil adjacent the rear wall, comprising a detachable jacket adapted to enclose said coil, said jacket being of metal and forming the 15 rear wall of the provision chamber and having spaced openings at intervals and inwardly extending shelves at said openings, and doors to close said openings.
5. In a refrigerator having an upstanding cooling coil for the passage of a refrigerant arranged adjacent one wall of the refrigerator, a jacket enclosing the coil and formed with openings opposite the spaces between the convolutions of the coil, supports within the jacket adjacent the open- 20 25
- ings for supporting pans containing water, and means for detachably securing the jacket against a wall of the refrigerator, consisting of movable securing elements carried by the refrigerator wall, and projections on the jacket engaged by said elements.
6. In a refrigerator having an upstanding cooling coil for the passage of a refrigerant located adjacent one wall of the refrigerator, a jacket enclosing the coil and 30 having its rear side open and engaging against the refrigerator wall nearest the coil, said jacket having its front formed with openings and provided with doors normally closing the same, supports within the jacket 35 adjacent the openings, and means for securing the jacket against said wall, consisting of turn buttons pivoted on said wall, and outturned flanges at the edges of the open side of the jacket engaged by said turn buttons.

In testimony that I claim the foregoing as my own, I have hereto affixed my signature.

OTTO A. LABUS.
